TELEGRAPH APPARATUS

Fred Warburton, London, England, assignor to
Cable and Wireless Limited, London, England,
a British company

Application June 19, 1939, Serial No. 279,951
In Great Britain June 23, 1938

23 Claims. (Cl. 178—33)

Telegraph receiving apparatus is generally provided with mechanism arranged to undergo cyclic movements at a frequency substantially equal to the speed at which signal elements are received. If a signal element of a given character, for example, a marking element, is effective in a cycle, the apparatus is operated to perform a function in that cycle corresponding to the signal element received. This function may be the perforation of tape, or the setting of a teleprinter permutation member, or the actuation of a retransmitting device, in accordance with the nature of the signal element received. This element may, if the apparatus is arranged to operate under the control of cable Morse code, be either a positive or a negative current impulse.

As is well known, signal elements may be considerably distorted upon reaching receiving apparatus. The distortion is usually least at the centre of each element, and for that reason it is best to arrange the mechanism undergoing cyclic movements to perform its selecting function to be controlled in accordance with the character of a signal element at an instant occurring at the centre of the corresponding cyclic movement. However, it is possible for the signal elements to become out of phase with the cyclic operation of the receiving apparatus, and in that event, the mechanism may fail to respond to a received signal element.

It is the object of the present invention to provide apparatus which, in the event of a received signal element being seriously out of phase with the receiving apparatus, maintains the effect of the received element for a sufficient period to enable it to become effective in the next cycle.

According to the invention, telegraph receiving apparatus is provided with mechanism arranged to undergo cyclic movements at a frequency substantially equal to the speed at which signal elements are received for determining at two instants in each cyclic movement whether a signal element of a given character is in transit at those instants and arranged to control means for retaining the effect of the signal element during the next cyclic movement if the signal element is in transit at one of the instants but not at the other. Thus, even when a "block" signal is received, that is a number of consecutive elements of the same character or kind, i. e. "marking elements," without an intervening "spacing" element, each of the consecutive elements, including the last, is effective. The said mechanism forms part of or is arranged to move in timed relationship with the mechanism which takes part in the performance of functions in accordance with received signal elements.

Advantageously, the instant occurring first may be substantially at the centre of each cyclic movement while the second instant occurs sub-

stantially at the end of such movement, the apparatus being arranged so that if the element is in transit only at the second instant, the effect of the element is maintained during the next cyclic movement. Thus, it will be seen that if an element is not effective at the first instant, the apparatus is in condition to retain the effect of an element provided that element arises at the second instant. The reason for determining whether or not a signal element is in transit at both instants is that, if the apparatus was set to retain the effect of a marking element, i. e. a signal element of the given character, according to whether or not such signal element was in transit only at one instant, the means for retaining the effect of the element would be operated by spacing elements and there would be no distinction between marking and spacing conditions.

Conveniently the mechanism may also be arranged to control the phase relationship between the said cyclic movements and the said incoming signals. Then, if a signal element is slightly out of phase with the corresponding cyclic movement, the necessary adjustment is made automatically so that ensuing elements are substantially in phase with the cyclic movements. It will be understood that provided the phase relationship is only slightly out of adjustment, it is only necessary to correct the phasing because, in spite of the slight lead or lag of an element in relation to its corresponding cyclic movement, the element is still received at a time which enables the associated function to be performed in that cyclic movement. When, however, the element is so badly out of phase that the function cannot be performed in the corresponding cyclic movement, the aforesaid means for retaining the effect of the element becomes operative so that the corresponding function is performed in the next cyclic movement and the means for controlling the phase relationship may thereafter become effective to maintain an ensuing element properly timed in relation to the cyclic movements of the mechanism.

In order that the invention may be clearly understood and readily carried into effect, apparatus in accordance therewith will now be described, by way of example, with reference to the accompanying drawings, in which:

Figure 1 is a perspective view of certain parts of the apparatus;

Figure 2 is a diagram for use in explaining the operation of the apparatus;

Figure 3 is a diagram of an electrical circuit under the control of the apparatus shown in Figure 1; and

Figure 4 is a further circuit diagram showing apparatus used in association with the apparatus of Figures 1 and 3.

Referring to the mechanism of Figure 1, this includes a shaft 1 which may be regarded as part of, or in driven engagement with, the main shaft of a telegraph receiving apparatus. The latter may, of course, be a retransmitter or it may be arranged to print characters or perforate tape in accordance with received signals. The shaft 1 rotates continuously during the operation of the receiving apparatus and makes one complete revolution for each signal element received. When the mechanism is incorporated in the telegraph printing apparatus particularly described in my British Patent specifications Nos. 463,975, 463,976 and 463,977, the shaft 1 would form part of or be geared to the shaft 84 of those specifications. The mechanism can be arranged for operation under the control of cable Morse code, double current cable code or Wheatstone Morse code, and will be described in relation to cable Morse code, in which the signal elements are of three different kinds, namely, a spacing or no-current element, a positive marking element and a negative marking element. The positive and negative elements represent respectively dots and dashes, or vice versa.

Fixed to the shaft 1 are four eccentrics 2a, 2b, 2c and 2d, embraced respectively by rings forming parts of eccentric rods 3a, 3b, 3c, and 3d. The eccentrics are set out of phase relatively to each other so that the eccentric rods 3a, 3b, 3d and 3c rise and fall in succession for each revolution of the shaft 1. The eccentric rods 3a—3d are pivoted respectively to four levers 4a, 4b, 4c and 4d, which are mounted to swing independently of each other about a fixed spindle 5. To the free ends of the levers 4a—4d, are pivoted at 4w, 4x, 4y and 4z respectively four selecting members 6a, 6b, 6c and 6d. These selecting members are in the form of bell cranks and are formed at the ends of their substantially horizontal parts with downwardly-extending lugs 7a, 7b, 7c and 7d.

For each marking signal element received, i. e., for each positive or negative element but not for a spacing element, an electromagnet 8 is energised to attract an armature 9, the armature being swung about an axis at its lower end. Each time the armature 9 is attracted, its upper end 9a, bearing against four levers 10a, 10b, 10c and 10d, swings them in an anti-clockwise direction (as viewed in Figure 1) about a fixed spindle 11 respectively against the action of four wire springs 12a, 12b, 12c and 12d which are bent round a fixed rod 13 with their upper free ends bearing against a fixed stop bar 14. When the electromagnet becomes de-energized, the armature 9 can be pushed back by one or more of the springs 12a—12d acting on the levers 10a—10d. The levers 10a—10d are associated respectively with four controlling members 15a, 15b, 15c and 15d, the latter, like the levers 10a—10d, being pivoted independently about the spindle 11. The levers 10a—10d are formed respectively with the lateral lugs 16a, 16b, 16c and 16d from which project respectively wire springs 17a, 17b, 17c and 17d, the upper ends of which engage projections 18a, 18b, 18c and 18d, formed on the controlling members 15a—15d.

Now consider the action, for example, of the lever 10a when this is swung about the spindle 11 by the armature 9. The associated controlling member 15a is also swung about that axis by the action of the wire spring 17a on the projection 18a, the right hand edge (as viewed in Figure 1) of the selecting member 15a being held by that spring in engagement with the lug 16a. The

lever 10a and the controlling member 15a, therefore, swing as a unit about the spindle 11. The controlling members 15a—15d are formed respectively at their lower ends with lateral lugs 19a, 19b, 19c, and 19d, which co-operate respectively with the lugs 7a—7d of the selecting members 6a—6d. Thus, when the controlling member 15a is swung in an anti-clockwise direction, its lug 19a is moved beyond the right hand edge of the associated lug 7a. If the phase relationship between the incoming signal, i. e. the movement of the armature 9, and the rotation of the shaft 1 is such that the bottom edge of the lug 7a on the selecting member 6a is carried downwards, through the medium of the associated eccentric 2a, beyond the top edge of the lug 19a after the latter has been swung to the right, the selecting member 6a will not be interfered with. On the other hand, if the lug 19a is still in its left hand position when the bottom of the lug 7a reaches the top of the lug 19a, the lug 7a will bear on the top of the lug 19a, so that, while the selecting member 6a continues its downward movement, it is swung in a clockwise direction about its pivot 4w. There are, therefore, two possible paths of movement for the selecting member 6a and in each reciprocation one of these movements is selected in accordance with the position of the controlling member 15a at the instant when the bottom of the lug 7a registers with the top of the lug 19a. In the upper part of its travel, the selecting member 6a is held against a fixed rod 20 by a wire spring 21a fixed to the eccentric rod 3a and in engagement with the selecting member 6a. There are, of course, three further springs 21b, 21c and 21d associated respectively with the selecting members 6b, 6c and 6d and arranged similarly to the spring 21a. When the lug 7a engages the top of the lug 19a, the selecting member 6a swings away from the rod 20, but when the lug 19a is moved to the right, the selecting member 6a lies against the rod 20 throughout its reciprocation.

Means are provided for locking each of the controlling members 15a—15d into one or other of its two positions as soon as the corresponding selecting member coacts with it. Associated respectively with the selecting members 6a—6d are four wire springs 21a, 21b, 21c and 21d which are bent round the spindle 5 and at their right hand end bear against a fixed rod 29. The left hand ends of these springs 21a—21d co-operate with notches 28a, 28b, 28c and 28d, formed respectively in the controlling members 15a. These springs rest respectively on the levers 4a—4d and have a downward bias so that they tend to follow the movements of these levers as they are swung about the spindle 5. Accordingly, in the event of the controlling member 15a, for example, not having been swung in an anti-clockwise direction from the position of Figure 1 at the instant when the lug 7a engages the top of the lug 19a, the tip of the spring 21a will have moved downwards with the lever 4a so far as to engage the right hand edge of the controlling member 15a, beneath the notch 28a, to prevent the controlling member 15a from being swung to the right by the engagement of the lever 10a by the armature 9. Thus, as soon as the selecting member 6a has explored the position of the controlling member 15a, the latter is locked in its left hand position until the selecting member 6a has been raised sufficiently for the lug 7a to part from the lug 19a. When, however, the lever 4a is raised sufficiently for the lug 7a to be above

the lug 19a and out of contact therewith, the left hand tip of the spring 18a is raised opposite the notch 28a so that the controlling member 15a can be swung in an anti-clockwise direction, the tip of the spring 27a then entering the notch 28a. When this condition arises, the controlling member 15a is held against returning in a clockwise direction as soon as the right hand edge of the lug 1a overlaps the left hand face of the lug 19a and cannot return until the selecting member 6a has been raised sufficiently for the lug 1a to clear the lug 19a, even although the electromagnet 8 may already have become de-energized. So long as the lug 1a overlaps the lug 19a the spring 27a, being engaged by the bottom edge of the notch 28a, does not follow the lever 4a.

Accordingly, when the armature 9 is attracted in a period when the lug 1a is engaging the top of the lug 19a and the controlling member 15a is held against movement in an anti-clockwise direction by the tip of the spring 27a engaging beneath the notch 28a, the armature movement is not held up because the lever 10a can still be swung in an anti-clockwise direction while the spring 17a yields and the lug 16a swings away from the controlling member 15a.

Switch levers 24a, 24b, 24c and 24d are pivoted independently upon a spindle 25 and are under the action respectively of wire springs 26a, 26b, 26c and 26d, each of which is bent over the spindle 25 and, at one end, engages its respective switch lever and, at the other end, the fixed rod 29. These springs tend always to hold the switch levers 24a—24d up against a fixed rod 30. They can, however, be held away from the rod 30 by latch levers 30a, 30b, 30c and 30d pivoted on a fixed spindle 31 and urged clockwise about this spindle respectively by wire springs 32a, 32b, 32c and 32d, each of which is bent over the spindle 31 and, at one end, engages its respective latch lever and, at the other end, a fixed rod 33. When the switch levers 24a—24d are in their uppermost positions, the latch levers rest behind lugs 34a, 34b, 34c and 34d on the switch levers 24a—24d.

Now, consider the switch lever 24a when in the position shown in Figure 1, that is, when in its uppermost position. If the selecting member 6a, in moving downwards, is not affected by the lug 19a on the controlling member 15a (the latter being in its right hand position), a lug 22a on this selecting member engages a lug 23a on the switch lever 24a, so that the latter is depressed, being swung in an anti-clockwise direction about the spindle 25. The switch lever 24a is depressed in this manner sufficiently for the lug 34a thereon to pass beneath the level of a shoulder 30w formed on the associated latch lever 30a. The latter is thus freed to be moved a little in a clockwise direction by the spring 32a, so that the lug 34a is held beneath the shoulder 30w. Accordingly, when the selecting member 6a is raised again, the switch lever 24a does not follow it but is held in its lowermost position by the latch lever 30a.

In the alternative condition, when the switch lever 24a is unlatched and the selecting member 6a is swung in a clockwise direction about its pivot 4w as a result of the engagement of its lug 1a with the lug 19a, the lug 22a on the selecting member 6a traverses a path such that it passes to the right hand side of the lug 23a. Therefore, the switch lever 24a is not depressed. Supposing, however, that the switch lever 24a has been depressed and is held in its lowermost

position by the latch lever 30a, then, in the next reciprocation of the selecting member 6a, the latter has no effect on the latched switch lever 24a if the lug 19a is in its right hand position so as to permit the selecting member 6a to remain in contact with the rod 20. On the other hand, if, in this next reciprocation, the lug 1a engages the top of the lug 19a so that the selecting member 6a is swung clockwise about its pivot 4w, a nose 35a at the upper end of the selecting member engages the left hand edge of the latch lever 30a and swings the latter anti-clockwise to release the switch lever 24a to its uppermost position. It will be seen, therefore, that if the selecting member 6a is swung clockwise about its pivot 4w, the switch lever 24a is allowed either to remain in its upper position or is caused to return to its upper position. In the other condition, when the selecting member 6a remains against the rod 20, the switch lever 24a is either forced downwards to its lowermost position or, if already there, is allowed to remain in that position.

The actuation and effect of the selecting members 6b, 6c and 6d is precisely the same as that described above in respect of the selecting member 6a. The selecting members 6b, 6c and 6d are formed respectively with noses 35b, 35c and 35d and with lugs 22b, 22c and 22d in precisely the same way as the selecting member 6a. Further, the switch levers 24b, 24c and 24d are formed with lugs 34b, 34c and 34d corresponding to the lug 34a. These lugs co-operate with shoulders 30x, 30y and 30z on their respective latch levers 30b, 30c and 30d in the same way as the lug 34a co-operates with the shoulder 30w. However, only the switch levers 24b and 24d are formed with lugs 23b and 23d similar to the lug 23a. The lug 23c for the switch lever 24c is not formed on that member but is formed on a member 36 which is under the control of the latch lever 30b.

The latch lever 30b is formed with a substantially horizontal extension 30x' which carries a leaf spring 37 extending through a slot in a lug 38 forming part of a bell crank lever 39 pivoted on a spindle 40. A jaw 41 is formed at the lower end of the bell crank lever 39 and a lug 42 formed on the member 36 passes loosely through this jaw. The member 36 is formed at its upper end with a slot 36x through which the spindle 40 passes. Therefore, when the latch lever 30b is turned about the spindle 31, the bell crank lever 39 is turned about the spindle 40 by the leaf spring 37. The member 36 is caused by the jaw 41 to partake of this swinging movement, but, by virtue of the slot 36x and the sliding engagement between the jaw 41 and the lug 42, the member 36 can move longitudinally relatively to the bell crank 39, so that the lug 23c rests on the top of the switch lever 24c in all positions of the bell crank lever 39. When the latch lever 30b is in its latching position, the lug 23c is withdrawn to a position in which it cannot be engaged by the lug 22c but, when the latch lever 30b lies in its right hand position, the position of the lug 23c corresponds to that of the lugs 23a, 23b and 23d.

The control of the switch lever 24c is, therefore, unlike the control of the other three switch levers in that it depends, not only upon the movement of the selecting member 6c, but also upon whether the lug 23c is in the position to be engaged at all by the lug 22c.

The switch levers 24a—24d are formed

respectively with arms 50a, 50b, 50c and 50d, which respectively operate four switches a, b, c and d, shown diagrammatically in Figure 3. These switches have spring contacts, and when the switch levers 24a-24d are all in their uppermost or unlatched positions, the contacts occupy the positions relatively to each other shown by full lines in Figure 3, so that no circuit is completed through a battery 51 or other source of electric current and either of two electromagnets 53 and 54 when a cam 179 on the shaft 1 is holding spring contacts 180 and 181 together. These electromagnets are associated with apparatus for momentarily speeding up or momentarily slowing down the shaft 1. Such apparatus is shown in British Patent specification No. 238,622, and the shaft 3 in that specification may be regarded as corresponding to the shaft 1 in the present specification, while the electromagnets 28 and 29 in this prior specification correspond to the electromagnets 53 and 54 in Figure 3. When any of the switches a, b, c and d are in the condition shown in full lines in Figure 3, they can be referred to as being in their "normal" condition. When the switch a is changed from its normal condition to its "operated" condition by the depression of the switch lever 24a, a contact 43y engages a contact 43w, while a contact 43z is separated from a contact 43x. Similarly, when the switch b is operated a contact 44y is changed over from a contact 44x to a contact 44w, while a contact 44r is changed over from a contact 44s to a contact 44v. In similar circumstances in the switch c, a contact 45y is changed over from a contact 45v to a contact 45w, while a contact 45x is pressed upon a contact 45z. When the switch d is operated a contact 46y is changed over from a contact 46x to a contact 46w. Thus, in each switch the movable contact or each movable contact is changed over to the dotted line position (Figure 3) when the switch is operated.

In Figure 2 the ordinates represent instants of time in revolutions of the shaft 1. Thus, the instant c' occurs at the end of one revolution of the shaft, while the instant c defines the finish of the next revolution of that shaft. Further, the ordinates a, b, c and d represent the instants in the last mentioned revolution of the shaft 1 at which the selecting members 6a-6d are caused by their respective eccentricities 2a-2d to co-operate with the switch levers 24a-24d either to latch them up or to unlatch them or to leave them where they are. It will be seen, therefore, that it is at these instants that the mechanism of Figure 1 differentiates between marking and spacing conditions. It will also be seen that the selecting instant b occurs when the shaft 1 has completed one half of its revolution, while the selecting instants a and d occur just before and just after the instant b. The instant c occurs just as the shaft completes a revolution. To enable the selecting instants a and d to be adjusted relatively to the selecting instant b, the eccentricities 2a and 2d are formed on collars 2w and 2x secured to the shaft 1 by set screws 2y and 2z. The adjustment is effected by loosening these set screws, turning the collars on the shaft 1, and then tightening the set screws. The eccentricities 2b and 2c are fixed permanently 180° apart.

Furthermore, it will be seen that Figure 2 represents two further cycles of the shaft 1, respectively defined between the pairs of ordinates c and c', c' and c''.

Now, as indicated above, a circuit can only be closed through one of the electromagnets 53 and 54 when the cam 179 is holding the contacts 180-181 together. The cam 179 is so formed as to close these contacts for a period beginning just after the instant d in one cycle and ending just before the instant a' in the next cycle. Thus, the periods during which the contacts 180 and 181 are closed are represented in Figure 2 respectively by the space up to the ordinate x, that between y and x', that between y' and x'' and that between y'' and c''. So far as the electromagnets 53 and 54 are concerned, it is only during these periods that the condition of the switches a, b, c and d need be considered, because it is only then that a circuit can be closed through battery 51 and one of the electromagnets.

In ideal working conditions each marking signal element would be received substantially in phase with one revolution of the shaft 1 and would extend substantially over the period occupied by that revolution. However, line conditions are often such that signal elements do not arrive in phase with the receiving apparatus, and signal elements often become considerably shortened in transit. First, however, let the marking element represented in the line I-I in Figure 2 be considered, this element being fairly nearly in phase with the revolution of the shaft 1 represented by the space between the ordinates c' and c and being of a length substantially equal to the time taken for that revolution. Thus, the armature 9 is attracted by the electromagnet 8 (Figure 1) before the instant represented by the ordinate a and remains attracted until an instant occurring between the ordinates c and a'. The result is that each of the switch levers 24a, 24b and 24d is moved to its latched position when its associated selecting instant occurs. On the other hand, the switch lever 24c is left unlatched because when the lug 22c arrives in position to engage the lug 23c, the latter will have been removed to its inoperative position by the prior movement of the latch lever 30b to its latching position. Accordingly, throughout the period represented between the ordinates y and x', when the contacts 180 and 181 are closed, the switches a, b and d are in their operated condition while the switch c is in its normal state. Thus, the movable contacts in the switches a, b, and d are in the dotted line positions in Figure 3 while the movable contacts in switch c are in the full line positions. Therefore, when the contacts 180 and 181 are closed by the cam 179, no circuit is completed through either of the electromagnets 53 and 54 and no retardation or advance of the shaft 1 is brought about. This, of course, is what is required because the marking element is sufficiently in phase with the shaft 1.

It is, in fact, the relationship between the incoming marking element and the instant b that is important because it is at that instant that a function, to be performed in accordance with the incoming element, is determined by the element. In telegraph receiving apparatus working in accordance with cable Morse code there are two relays, one of which is operated upon receipt of a dot element and the other upon receipt of a dash element. The energization of either of these relays conditions associated mechanism to be operated, by a member undergoing cyclic movement in timed relationship with the shaft 1, to perform a function. This function may be the perforation of tape, or the setting of

a teleprinter permutation member, or the setting of a retransmitter relay armature in accordance with the dot or dash element received. Now the received marking element may be shortened between the transmitter and receiver and if the element is in phase with the shaft 1, the most effective part of the element will probably arrive substantially at the instant *b*. It is for that reason that the member moving in timed relationship with the shaft 1 is arranged to cause the mechanism to perform the function at the instant *b* in the centre of the associated revolution of the shaft 1. The marking element may, of course, arrive so late that it misses the instant *b* entirely and it is a particular feature of the invention to provide for such a condition but a description of this will be deferred until the signal represented by the line III-III is dealt with.

Returning now to the signal condition represented by the line I-I, it will be seen that, even if the marking element is shortened by the amount indicated by the dotted line *n* the instant *b* is still well within the scope of the marking element and the switch condition is the same as that described above, because the switches *a*, *b* and *d* are in their operated condition at the instant *y*.

Now, suppose that a marking element following a spacing element arrives somewhat late in relation to the associated revolution of the shaft 1 (represented by the space between the ordinates *c* and *c'*) as indicated by the line II-II, the selecting instant *a* occurs before the arrival of the first part of the marking element, that is before the armature 9 is drawn up by the electromagnet 8. However, the armature 9 is drawn up before the selecting instant *b* has occurred. As the selecting instants occur, therefore, the switch lever 24a is not latched up, being left in its raised position, but the switch levers 24b and 24d are depressed and latched. Thus, when the cam 179 closes the contacts 180 and 181 at the instant *y*, the switches *b* and *d* only are operated, so that the movable contacts in the switches *b* and *d* are in the dotted line positions (Figure 3) while the movable contacts in the switches *a* and *c* are in the full line positions. A circuit is, therefore, completed from the battery 51, through contacts 180 and 181, contacts 46y and 46w in switch *d*, contacts 43z and 43x in switch *a*, contacts 44y and 44w in switch *b*, electromagnet 53, back to battery 51. When the instant *c* arrives there is no change in the condition of the switches because the switch lever 24c cannot be latched owing to the lug 23c being in its inoperative position as a result of the latching of the switch lever 24b. Accordingly, throughout the period between the ordinates *y* and *x'*, that is so long as the cam 179 holds the contacts 180 and 181 closed, the electromagnet 53 is energised while the electromagnet 54 remains de-energised. The effect of energising the magnet 53 is, through the medium of the mechanism described in the aforementioned British Patent specification No. 238,622, to slow down or retard the shaft 1 during the period represented between the ordinates *y* and *x'*. It will be seen that this is necessary because the instant *b* occurs dangerously near the beginning of the signal element and not sufficiently near the centre thereof. The momentary slowing down of the shaft 1 results in the selecting instants in respect to the next revolution of the shaft 1 occurring somewhat later than would otherwise be the case. The movement of the shaft

1 is, therefore, brought more into the correct time relationship with the next signal element and the selecting instant *b* for that element occurs nearer the centre thereof. Speaking in the terms of Figure 2, all the ordinates to the right of the ordinate *c* are moved further to the right.

It may be mentioned that, even if the marking element shown in the line II-II is shortened to the extent shown by the dotted line *m*, similar conditions obtain because, between the ordinates *y* and *x'*, the switches *b* and *d*, but not the switches *a* and *c*, are in their operated condition.

Now consider the case shown by the line III-III where a marking element, following a spacing element, arrives so late in relation to the corresponding revolution of the shaft 1 that it misses the instant *b* but begins before the instant *d*. Then, when the instant *y* arises at which the cam 179 closes the contacts 180 and 181, only the switch *d* is operated. Therefore, a circuit is completed from battery 51, through contacts 180 and 181, contacts 46y and 46w in switch *d*, contacts 43z and 43x in switch *a*, contacts 44y and 44w in switch *b*, the electromagnet 54, back to the battery 51. Accordingly, the electromagnet 54 is energised, and not the electromagnet 53, so that the shaft 1 is speeded up or advanced to bring the selecting instants in the next revolution of the shaft 1 still further out of phase with the incoming signals. The reason for this is that when a signal element is so late that it misses the instant *b*, the apparatus is arranged to have its effect in the revolution of the shaft 1 following the revolution in which the beginning of the signal is received. Thus, the function to be performed in accordance with the marking element in the line III-III is determined at the instant *b'* which is brought somewhat nearer the left than is shown in Figure 2, and consequently nearer the centre of the marking element by the advancing of the shaft 1.

The marking element may, however, be shortened so that, in spite of the advancing of the instant *b'*, the marking element does not overlap that instant. The marking element may, in fact, be shortened as much as is shown by the dotted line *o*. It is therefore necessary to provide means for retaining the effect of the marking element until the instant *b'* and it is one of the functions of the switch *c* to control the maintenance of a marking element when its phase relationship with the movements of the shaft 1 is substantially as shown by the line III-III. Referring again to that line it will be seen that the switch *c* is operated at the instant *c* owing to the fact that the latch lever 30b is in its unlatching position so that the lug 23c is interposed beneath the lug 22c on the selecting lever 6c so as to enable the latter to depress the switch lever 24c. In this connection it may be repeated that the switch lever 24c is only operated when the latch lever 30b is in its unlatching position as a result of no marking element being in transit at the instant *b*.

The operation of the switch *c* at the instant *c* has no effect on the circuit which has been completed through the electromagnet 54 which remains energised until the circuit is broken by the action of the cam 179 at the instant *x'*.

The closing of the contacts 45x and 45z in the switch *c* connects conductors 62 and 63 which are incorporated in the receiver circuit as shown in Figure 4. Referring to the latter, a relay 64 is the line relay through which the signals from a distant transmitter pass. This relay has an

armature 65 which takes up the central position shown when a no-current condition obtains, as in spacing signal elements. When a marking element of one kind, e. g. a dot, is received, the armature 65 is swung to the left against a contact 66. This results in a circuit being completed through a source 67 of electric current and an electromagnet 68. The latter then draws up an armature 69 so as to complete a circuit through a winding 70 of a locking relay, a function relay 71, and the current source 67.

A second function relay 72 is operated when the line relay armature is swung to the right against a contact 73, by a marking element of the other kind, e. g. a dash. The armature 65 is thus caused to close a circuit through an electromagnet 74 so that an armature 75 is drawn up and a circuit through a locking relay winding 76 and the function relay 72 is closed. The function relays 71 and 72 are the aforementioned relays which condition associated mechanism to be operated by a member undergoing cyclic movement in timed relationship with the shaft 1. When printing telegraph apparatus as described in Patent No. 2,148,002 is to be operated under the control of the function relays, the latter actuate the armatures 45 and 46 in that patent, while the member moving in timed relationship with the shaft 1 is the actuator 7 in that patent. The actuator operates mechanism for selecting pairs of permutation members and the aforesaid armatures 45 and 46 take part in the selection of one permutation member in each selected pair. The selection of the permutation members determines the actuation of mechanism for printing type and the said actuator selects the pairs of permutation members under the control of a further armature which is actuated whenever a marking signal element arises. This armature would be controlled by an electromagnet 77, arranged, as shown by dotted lines in Figure 4 of the present specification, so as to be energised whenever the function relay 71 or the function relay 72 is energised. It will be seen also that the electromagnet 8 is energised whenever the armature 69 or the armature 75 is drawn up.

On the shaft 1 is a cam 79 which closes contacts 80 and 81 for a period during each revolution of the shaft 1. This period begins before the instant *a* or *a'* etc. and ends after the instant *b* or *b'* etc. Therefore, soon after the switch *c* is operated, the contacts 80 and 81 are closed. Returning to the phase relationship shown in line III-III, it will be seen that the switch *c* is operated while current is passing through the winding 70 of the left-hand locking relay and through the function relay 71, that is, while the locking relay winding 70 is attracting an armature 82 against a contact 83. Accordingly, as soon as the contacts 80 and 81 are closed, a circuit is completed through a second winding 84 of the left-hand locking relay. Thus, assuming that the signal element is shortened so that the armature 69 is allowed to return to its unattracted position before the selecting instant *b'* occurs, the function relay 71 will not immediately become de-energised but will be maintained in its energised condition by current passing through the contacts 80 and 81, the contacts 45x and 45z, the contact 83 and armature 82, and the locking relay winding 84, the latter serving to hold the armature 82 against the contact 83 after the locking relay winding 70 has become de-energised. This condition is maintained until the cam 79 allows the contacts 80 and 81 to sepa-

rate, that is, until the selecting instant *b'* has passed. Therefore, the function relay 71 is maintained in its energised state long enough to condition the associated mechanism to be operated, for the performance of the function associated with the marking element, in the revolution of the shaft 1 subsequent to the revolution in which the first part of the signal is received.

When the received signal element is a dash element a similar action takes place, but in that case a second winding 85 of the right hand locking relay maintains an armature 86 against a contact 87, so that the dash relay 72 is maintained energised until the cam 79 allows the contacts 80 and 81 to separate.

It will be seen that the locking relays and the parts associated with those relays constitute the aforementioned means provided for retaining the effect of a signal element when a condition such as that shown in the line III-III arises.

The conditions that arise when a marking element as shown in the line IV-IV is in transit are very similar to the conditions that obtain in respect of the signal condition shown by the line III-III. In the line IV-IV it will be seen that a marking element arrives just before the instant represented by the ordinate *c* so that while the contacts 180 and 181 (Figure 3) are closed a circuit is completed from the battery 51 through the contacts 180 and 181, the contacts 46y and 46x in switch *d*, the contacts 45y and 45w in switch *c*, the electromagnet 54 back to battery 51. Thus, again the shaft 1 is speeded up or advanced so as to bring the subsequent selecting instants somewhat nearer to the centre of the received marking element, that is to say the effect is to shift somewhat to the left the ordinates on the right of the ordinate *c* in Figure 2. Again the operation of the switch *c* serves to retain the effect of the received element until the instant *b'*, even although the marking element may be shortened to the extent indicated by the dotted line *p* applied to the line IV-IV, in which event the received marking element would not overlap the instant *b'*.

In the condition shown by the line V-V in Figure 2 a somewhat shortened marking element embraces the instants *a* and *b* but finishes before the instant *d*. Therefore, throughout the period defined between the ordinates *y* and *x'* the switches *a* and *b* are operated. The switch *c* of course, is not operated because the switch *b* is operated. Thus, when the cam 179 is closing the contacts 180 and 181, a circuit is completed from the battery 51 through the contacts 181 and 180, the contacts 46y and 46x in the switch *d*, the contacts 45y and 45v in the switch *c* the contacts 43w and 43y in the switch *a*, the contacts 44t and 44v in the switch *b*, the electromagnet 54, and back to battery 51. Thus, the electromagnet 54 is energised to advance the shaft 1 during the period between the ordinates *y* and *x'*. This serves to bring the subsequent selecting instants more accurately in phase with the incoming signal, as is required by the fact that the instant *b* occurs dangerously near the end of the marking element shown by the line V-V.

It is a particular feature of the apparatus that it is equally effective when block signals are received, that is to say, a series of marking elements in sequence having the effect of a single prolonged marking element. One such block signal is shown in line VI-VI where two marking elements, each occupying the time taken for a single revolution of the shaft 1, are joined to-

gether. When the first part of this block signal is received the condition is precisely the same as that described with reference to the signal of the line IV-IV, that is to say that the switch *c* is operated before the instant *x'* so that the shaft *l* is advanced slightly. However, when the cam 179 again closes the contacts 180 and 181 at the instant *y'*, all the switches *a*, *b*, *c* and *d* are operated, and the result of this is that neither of the electromagnets 53 or 54 is energised. The important fact, however, is that the switch *c* remains closed from the instant represented by the ordinate *c* until the instant represented by the ordinate *c''*. Accordingly, when the end of the block signal arrives the effect is retained. The function to be performed by the second half of the block signal is determined at the instant *b''*, and the necessity for retaining the effect of the signal through the switch *c* and circuits associated therewith, will be appreciated when the possibility is considered of the second element being shortened as indicated by the dotted line *q*.

In the appended claims, the reference to "an output circuit in which signal impulses are repeated" is to be interpreted broadly to apply to any apparatus controlled by the output circuit of the receiving relay, whether it be a printer, a retransmitter, or other suitable apparatus.

I claim:

1. In telegraph receiving apparatus, in combination, signal detecting means, means for operating said signal detecting means in cyclic movements at a frequency substantially equal to the speed at which signal elements are received and being operative to determine at two instants in each cyclic movement whether a signal element is in transit at those instants, and means controlled by said signal detecting means for retaining the effect of the signal element during the next cyclic movement if the signal element is in transit at only one of the two instants.

2. In telegraph receiving apparatus, in combination, a switch operating device having two operative positions, a selecting member, means for causing said member to undergo to-and-fro movement at a frequency substantially equal to the speed at which signal elements are received, an intermediate member, means for moving said intermediate member to and from an effective position enabling said selecting member to move said operating device from one operative position to the second, a second selecting member, means for causing, said second selecting member to undergo to-and-fro movement at a frequency substantially equal to the speed at which signal elements are received, signal responsive means operative to impart a further component of movement to each said selecting member to modify the path of movement thereof only when a marking signal element is in transit at a predetermined instant in the to-and-fro movement of the member, the predetermined instant in respect of the first-mentioned selecting member occurring later than that in respect of the second selecting member, and means controlled by the second selecting member, when traversing one of its paths, for causing said intermediate member to take up its effective position and, when traversing the other of its paths, to take up its other position, means controlled by the first-mentioned selecting member being operative, when traversing one of its paths, for causing said switch operating device to take up one of its positions

and, when traversing the other of its paths, causes said switch operating device to take up its other position when said intermediate member is in its effective position.

5. In telegraph receiving apparatus, in combination, two selecting members, means for causing each of said selecting members to undergo periodic to-and-fro movement, signal responsive means arranged to impart a further component of movement to each said selecting member to modify the path of movement thereof only when a marking signal element is in transit at a predetermined instant in the to-and-fro movement of the member, switch operating devices controlled respectively by said selecting members, each such device having two positions, one of which is selected by the associated selecting member at each to-and-fro movement of the member in accordance with the path of movement of that member, switches controlled respectively by said devices and means under the control of said switches for adjusting the phase relationship between received signal elements and the to-and-fro movements of said selecting members.

4. In telegraph receiving apparatus, in combination, signal detecting means, means for operating said signal detecting means in cyclic movements at a frequency substantially equal to the speed at which signal elements are received and being operative to determine, both at an instant occurring substantially at the middle of each cyclic movement and at an instant substantially at the end thereof, whether a signal element is in transit at those instants, and means controlled by said signal detecting means for retaining the effect of the signal element during the next cyclic movement if the signal element is in transit only at the second of the said instants.

5. In telegraph receiving apparatus, in combination, signal detecting means, means for operating said signal detecting means in cyclic movements at a frequency substantially equal to the speed at which signal elements are received and being operative to determine at two instants in each cyclic movement whether a signal element is in transit at those instants, means controlled by said signal detecting means for retaining the effect of the signal element during the next cycle of movement if the signal element is in transit at only one of the two instants, and means controlled by said signal detecting means for adjusting the phase relationship between the cyclic movements of said signal detecting means and the incoming signals.

6. In telegraph receiving apparatus, in combination, signal detecting means, means for operating said signal detecting means in cyclic movements at a frequency substantially equal to the rate at which signal elements are received and being operative to determine whether a signal element is in transit at four instants occurring respectively substantially at the middle of said cyclic movement, just before and just after that instant and substantially at the end of said cyclic movement, and means controlled by said signal detecting means for controlling the phase relationship between the cyclic movements and the incoming signals in accordance with the phase relationship between said instants and each particular signal element.

7. In telegraph receiving apparatus, in combination, selecting members and means for causing said members to undergo cyclic movements

at a frequency substantially equal to the speed at which signal elements are received and with predetermined phase displacements between the movements of certain of said selecting members, means responsive to received signal elements for modifying the path of cyclic movement of each selecting member when a signal element is in transit at a particular instant in such cyclic movement, and means for retaining the effect of a signal element under the control of one of said members, and means controlled by another of said members, when traversing one only of its paths, to permit the first-mentioned member to operate said retaining means.

8. In telegraph receiving apparatus, in combination, selecting members and means for causing said members to undergo cyclic movements at a frequency substantially equal to the speed at which signal elements are received but with phase displacement between the cyclic movements of the respective members, controlling members allocated respectively to the selecting members and arranged to move between two positions corresponding to marking and spacing signal conditions, means whereby each controlling member is effective when in one only of the two positions to modify the cyclic movement of its associated selecting member, signal responsive means for operating said controlling members between their two positions in accordance with incoming signals, means controlled by one of said selecting members when traversing one of its paths to retain the effect of a signal element during the ensuing cycle of movement of that member, and mechanism controlled by another of said selecting members in traversing a particular one of its two paths to prevent said first-mentioned selecting member from operating said retaining means when traversing either of its paths.

9. In telegraph receiving apparatus, in combination, mechanism including selecting members, means for operating said selecting members in cyclic movements at a frequency substantially equal to the speed at which signal elements are received with phase displacement between each such cyclic movement, as many switches as there are selecting members arranged to be controlled by the selecting members, each switch having two positions, one allocated to a marking signal condition and the other allocated to a spacing signal condition, and means responsive to received signal elements to operate each switch through the medium of the associated selecting member at a particular instant in the movement of that member, means for retaining the effect of a signal element under the control of one of said switches, and further means responsive to received signals for preventing said one switch from being operated if a marking element is in transit at the instant when the condition of a second switch is determined.

10. In telegraph receiving apparatus, in combination, signal detecting means, means for operating said signal detecting means in cyclic movements at a frequency substantially equal to the speed at which signal elements are received and operative to determine at two instants in each cyclic movement whether a signal element is in transit at those instants, and means controlled by said signal detecting means for retaining the effect of the signal element during the next cyclic movement if the signal element is in transit at only one of the said instants, said last-mentioned means including a locking relay under

the control of a switch, the condition of said locking relay being determined at the said one of the two instants.

11. In telegraph receiving apparatus, in combination, a plurality of driving members mounted for to-and-fro movement, means for imparting to-and-fro movements to said members with phase displacement between said movements and frequencies substantially equal to the speed at which signal elements are received, a plurality of selecting members respectively pivotally connected to said driving members, means responsive to incoming signals and operative to turn each selecting member about its pivotal connection if a signal element is in transit at a predetermined point in the to-and-fro movement of the associated driving member, switch operating members allocated respectively to said selecting members, latch members allocated respectively to said operating members, and means including switches operable by said operating members for controlling the phase relationship between said to-and-fro movements and the received signal elements, and means controlled by said selecting members for successively and selectively determining in which of two positions each operating member shall lie, one such position being a position in which it is held by the associated latch member.

12. In telegraph receiving apparatus, in combination, mechanism including two selecting members, means for operating each selecting member in cyclic movements at a frequency substantially equal to the speed at which signal elements are received, retaining means under the control of one of said members for retaining the effect of a signal element, means responsive to incoming signals arranged at a predetermined instant in the cyclic movement of said one of said members to operate said retaining means through the medium of said member only when a signal element is in transit at that instant and when the second of said members is inoperative, said signal responsive means including means operative at a further instant to render said second selecting member operative if a signal element is in transit at the further instant.

13. In telegraph receiving apparatus, in combination, a signal responsive relay having an armature, means for causing said armature to take up an operative position when a marking signal element is received, two selecting members, means for causing said selecting members successively to co-operate with said armature in a period substantially equal to the time period occupied by a received signal element, and means controlled by said selecting members for retaining the effect of a signal element for a controlled period if said armature is in its operative position only when the second of said selecting members is in position to co-operate therewith.

14. In telegraph receiving apparatus, in combination, signal detecting means, means for operating said signal detecting means in cyclic movements at a frequency substantially equal to the speed at which signal elements are received and operative to determine at instants in each cyclic movement whether a signal element is in transit at those instants, electrical switches under the control of said signal detecting means, means for rendering said switches operative only during a predetermined part of the time occupied by each said cyclic movement, and means responsive to received signals for adjusting the phase relationship between the received signals

and said cyclic movements, said last-mentioned means being under the control of said switches when operative.

15. In telegraph receiving apparatus, in combination, a switch operating device having two operative positions, a selecting member, means for causing said member to undergo to-and-fro movement at a frequency substantially equal to the speed at which signal elements are received, an intermediate member arranged to be moved to and from an effective position enabling said selecting member to move said operating device from one operative position to the second, a second selecting member, means for causing said second selecting member to undergo to-and-fro movement at a frequency substantially equal to the speed at which signal elements are received, signal responsive means operative to impart a further component of movement to each said selecting member to modify the path of movement thereof only when a marking signal element is in transit at a predetermined instant in the to-and-fro movement of the member, the predetermined instant in respect of the first-mentioned selecting member occurring later than that in respect of the second selecting member, and means controlled by the second selecting member, when traversing one of its paths, for causing said intermediate member to take up its effective position and, when traversing the other of its paths, to take up its other position, means controlled by the first-mentioned selecting member, when traversing one of its paths, for causing said switch operating device to take up one of its positions and, when traversing the other of its paths, causes said switch operating device to take up its other position when said intermediate member is in its effective position, and means controlled by said switch operating device for retaining the effect of a marking signal element when said operating device is caused to take up its said other position.

16. In telegraph receiving apparatus, the combination of a receiving relay having an input circuit for receiving signal impulses and an output circuit in which signal impulses are repeated, signal detecting means, means operated synchronously with the incoming signals for controlling said signal detecting means to detect the presence of signal impulses at different instants in each signal cycle, and signal continuing means controlled by said detecting means and being responsive to receipt of a signal impulse which has been delayed beyond a predetermined point in any cycle for continuing the effect of said delayed signal in said output circuit during the next signal cycle.

17. Telegraph receiving apparatus according to claim 16 in which said signal continuing means is operative to continue the effect of a signal where the receipt of the signal is delayed beyond the midpoint of the signal cycle.

18. In telegraph receiving apparatus, the combination of a receiving relay having an input circuit for receiving signal impulses and an output circuit in which signal impulses are repeated, signal detecting means, means operated synchronously with the incoming signals for controlling said signal detecting means to detect the presence of signal impulses at different instants in each signal cycle, signal continuing means controlled by said detecting means and being responsive to the detection of a signal im-

pulse at an instant during the second half of the signal cycle for continuing the effect of said signal impulse in said output circuit during the next signal cycle, and means controlled by said detecting means and being responsive to the detection of a signal impulse at an earlier instant in said cycle for preventing operation of said signal continuing means.

19. In telegraph receiving apparatus, the combination of a receiving relay having an input circuit for receiving signal impulses and an output circuit in which signal impulses are repeated, signal detecting means, means operated synchronously with the incoming signals for controlling said signal detecting means to detect the presence of signal impulses at four different instants in each signal cycle, the first instant occurring during the first half of the signal cycle, the second instant substantially at the middle of the cycle, the third instant in the second half of the signal cycle, and the fourth instant at the end of the signal cycle, means for adjusting the phase between said synchronously operated signal detecting means and said incoming signals, and means for controlling said phase adjusting means by said signal detecting means to change the phase of said signal detecting means in response to abnormal signal conditions in said input circuit.

20. Telegraph receiving apparatus according to claim 19 in which the signal detecting means and phase adjusting means includes means to retard the phase of the phase adjusting means upon receipt of a signal impulse beginning between the first and second instants and continuing beyond the third instant.

21. Telegraph receiving apparatus according to claim 19 in which the signal detecting means and phase adjusting means includes means to advance the phase of the phase adjusting means in response to a signal impulse beginning after the second instant and continuing to the end of the cycle.

22. Telegraph receiving apparatus according to claim 19 in which the signal detecting means and phase adjusting means includes means to advance the phase of the phase adjusting means in response to receipt of an impulse beginning before the first instant and ending between the second and third instants.

23. Telegraph receiving apparatus according to claim 14 in which four electric switches are controlled by the signal detecting means in accordance with the signal conditions at four different instants in each signal cycle, the first instant occurring during the first half of the signal cycle, the second instant at substantially the middle of the cycle, the third instant in the second half of the signal cycle, and the fourth instant at the end of the signal cycle, means for preventing operation of the fourth switch corresponding to the fourth instant where the switch corresponding to the second instant is operated in any signal cycle, and wherein the phase adjusting means according to claim 14 is controlled by the operation of said switches to retard the phase upon operation of the first switch alone and upon the joint operation of the second and third switches in any cycle, and to advance the phase by operation of the fourth switch singly and by the joint operation of the first and second switches or the third and fourth switches in any given cycle.

FRED WARBURTON.
